UNITED STATES PATENT OFFICE.

FREDERICK H. GRISWOLD, OF SPRINGFIELD, MASSACHUSETTS.

DESIGN FOR A CULINARY VESSEL.

SPECIFICATION forming part of Design No. 37,205, dated November 1, 1904.

Application filed September 27, 1904. Serial No. 226,251. Term of patent 7 years.

To all whom it may concern:

Be it known that I, FREDERICK H. GRISWOLD, a citizen of the United States, residing at Springfield, in the county of Hampden and State of Massachusetts, have invented a new, original, and ornamental Design for a Culinary Vessel, of which the following is a specification.

The accompanying drawing represents my design for a culinary vessel in perspective.

What I claim as new is—
The ornamental design for a culinary vessel, as shown.

FREDERICK H. GRISWOLD.
